UNITED STATES PATENT OFFICE.

RICHARD RABY, OF YORK, PENNSYLVANIA.

BROOM-HEAD.

SPECIFICATION forming part of Letters Patent No. 536,295, dated March 26, 1895.

Application filed December 13, 1894. Serial No. 531,666. (No model.)

To all whom it may concern:

Be it known that I, RICHARD RABY, a citizen of the United States, residing at York, in the county of York and State of Pennsylvania, 5 have invented certain new and useful Improvements in Broom-Heads, of which the following is a specification.

My invention relates to an improved broom-head.

10 The object of the invention is to provide a device of this kind which is simple, light and cheap, and which may be very readily opened for the insertion of new broom straw and securely closed in order to clamp or hold the 15 straw in the form of a broom.

The invention will be hereinafter fully described in connection with the accompanying drawings, in which—

Figure 1 is a perspective view of my improved holder. Fig. 2 is a vertical section on the line *a—a* of Figs. 1 and 3. Fig. 3 is a partial edge view showing the manner of connecting the sections, and Fig. 4 is a section on the line *b—b* of Fig. 2.

25 My improved broom-head consists of two separable sections each having two side arms 1, lower connecting bars 2 which form the clamp to hold the broom straw, and upper cross bars or plates 3 which confine the ends 30 of the straw between them. The main section A has also a flat top plate 4 which, together with the side bars 3, forms a box-like receptacle for the ends of the straw. Extending upward from the center of this plate is a 35 socket for the broom handle. The ends of the plate 4 have notches 6 adjacent to the arms 1 and projections 7 adjacent to the notches.

The smaller section B of the broom-head has its side arms 1 extended upward and 40 formed into hooks 8 which are rounded at the back 9 and provided with notches 10 in front. The cross bar 3 of the movable section is provided with a projection 11 which is

adapted to enter the lower end of the socket to sustain the cross bar and prevent it from 45 bulging outward. The clamp 2 is connected by screws or bolts 12.

To fill the broom-head, the section A is laid down and the broom corn placed in it and properly arranged, with the upper or cut ends 50 close to the top plate 4. The section B is then applied in the manner illustrated in Fig. 3 by engaging the hooks 8 with the notches in the ends of the top plate. The lower end of section B is then pressed down and connected 55 with the lower clamping bar of the section A by means of the screws or bolts. The manner of interlocking the hooks on the section B with the notches in the top plate 4 very securely connects the two sections together and 60 prevents relative movement of any kind.

Having described my invention, what I claim, and desire to secure by Letters Patent, is—

As a new article of manufacture a broom-head composed of two separable sections, each section having two side arms, an upper cross-plate 3 and a lower clamping bar, one of said sections having a flat top plate 4 provided with a socket for the handle and with 65 notches in its ends, and the other section having its side arms extended upward and formed with notched hooks adapted to interlock with the sides of the notches in the top plate, a projection 11 on the upper edge of the cross-plate 70 adapted to enter the socket to brace said cross plate, and means for connecting the lower clamping bars, substantially as described.

In testimony whereof I affix my signature 80 in presence of two witnesses.

RICHARD RABY.
